UNITED STATES PATENT OFFICE.

GERHARD H. LIEFTUCHTER, OF CINCINNATI, OHIO, ASSIGNOR TO THE ELECTRIC RAILWAY EQUIPMENT COMPANY, OF CINCINNATI, OHIO, A CORPORATION OF OHIO.

DESIGN FOR A BRACKET FOR LIGHTING FIXTURES.

Application filed August 18, 1923. Serial No. 7,035. Term of patent 14 years.

To all whom it may concern:

Be it known that I, GERHARD H. LIEFTUCHTER, a citizen of the United States of America, and a resident of Cincinnati, in the county of Hamilton and State of Ohio, have invented a new, original, and ornamental Design for a Bracket for Lighting Fixtures, of which the following is a specification, reference being had to the accompanying drawing, forming part thereof.

The figure is a side elevation of a bracket for lighting fixtures, showing my new design.

I claim:

The ornamental design for a bracket for lighting fixtures as shown.

GERHARD H. LIEFTUCHTER.
